US0D1057403S

(12) United States Design Patent (10) Patent No.: US D1,057,403 S
(45) Date of Patent:  Jan. 14, 2025

(54) SLING BAG

(71) Applicant: Chaohan Deng, Guangzhou (CN)

(72) Inventor: Chaohan Deng, Guangzhou (CN)

() Term: 15 Years

(21) Appl. No.: 35/518,022

(22) Filed: Jul. 14, 2023

(80) Hague Agreement Data

Int. Filing Date: Jul. 14, 2023

Int. Reg. No.: DM/230559

Int. Reg. Date: Jul. 14, 2023

Int. Reg. Pub. Date: Aug. 4, 2023

(51) LOC (15) Cl. 03-01

(52) U.S. Cl.

USPC D3/217

(58) Field of Classification Search
